UNITED STATES PATENT OFFICE

FREDERICK R. ERBACH, OF DETROIT, MICHIGAN, ASSIGNOR TO KELVINATOR CORPORATION, OF DETROIT, MICHIGAN, A CORPORATION OF MICHIGAN

FLUID COOLER

Application filed April 11, 1927. Serial No. 182,650.

My invention relates to refrigeration, and particularly to providing a cabinet for refrigerating materials used in dispensing soft drinks, and the principal object of my invention is to provide a new and improved cabinet of this type. In the drawings accompanying this specification and forming a part of this application I have shown, for purposes of illustration, one form which my invention may assume, and in these drawings:

Figure 1 is a horizontal section through a cabinet embodying my invention,

Figure 2 is a section on the line 2—2 of Figure 1, while

Figure 3 is a section on the line 3—3 of Figure 1.

The embodiment of my invention disclosed herein comprises a cabinet 11 for dispensing soft drinks provided with at least one refrigerated compartment 12 in which is disposed a series of coil containers 13 for soft drink materials having their end turns 14 extended upwardly for connection with the dispensing faucets (not shown).

As is well known in the business of dispensing soft drinks the materials must be refrigerated, but the refrigerating temperature must not be reduced to the freezing point.

This would be likely to occur if the refrigerant expansion unit were disposed in close proximity to the container coils. I therefore provide a refrigerant expansion unit consisting of a coil 15 having its inlet 16 connected by a pipe 17 to the outlet of a refrigerant condenser (not shown) and its outlet 18 connected by a pipe 19 to the inlet of a refrigerant compressing mechanism (not shown), and disposed at a point sufficiently removed from the material containing coils 13 to prevent any freezing of the contents of the coils 13.

Such a disposition of the container coils and the expansion coils however is not conducive to the best refrigeration as the large body of brine between the coils 13 and the expansion coil 15 decreases the response of the expansion coil 15 to the demands of the material containing coils 13. To increase the speed of reaction of the expansion coil 15 to

the demands of the material containing coils 13 I attach to the refrigerant expansion coil 15 in position to extend into the space between the container coils 13 and the refrigerant expansion coil 15 relatively large plates 16 formed of material having high heat conductivity thus providing for removal of the heat promptly from the coils 13. 55

From the above disclosure it will be obvious to those skilled in the art that I have provided a cabinet for refrigerating soft drink materials in which an efficient refrigerating temperature can be maintained without danger of freezing such materials. 60

It will therefore be apparent to those skilled in the art that the embodiment of my invention herein shown and described accomplishes at least the principal object of my invention. 65

At the same time it also will be obvious to those skilled in the art that the embodiment of my invention herein shown and described may be variously changed and modified without departing from the spirit of my invention or sacrificing the advantages thereof, 70 and it therefore will be understood that the disclosure herein is illustrative only, and that my invention is not limited thereto. 75

I claim:

1. In a fluid cooling apparatus, a chamber 80 for containing heat transfer liquid, a fluid circulating coil submerged in the liquid at one side of said chamber, a refrigerant expander submerged in the liquid at the side of said chamber opposite said coil, said expander being connected with apparatus adapted to cause limited congealing of the liquid in said chamber therewith, and fins in intimate contact with said expander extending adjacent said fluid circulating coil, said fins being of sufficient length to penetrate the congealed fluid adhering to said expander. 85

2. A refrigerator unit for refrigerating soft drink fluid required to be maintained at a temperature higher than freezing, comprising: a cabinet having a refrigerated compartment containing a heat transfer liquid, container means for the liquid to be refrigerated located in said compartment, refrigerant expander means located in said com- 90

partment at a distance from said container means, and fin means carried by one of said means and extending outwardly therefrom into the space between said container means and said expander means adjacent the other of said means.

3. A refrigerator unit for refrigerating soft drink fluid required to be maintained at a temperature higher than freezing, comprising: a cabinet having a refrigerated compartment containing a heat transfer liquid, container means for the liquid to be refrigerated located in said compartment, refrigerant expander means located in said compartment at a distance from said container means, and fin means carried by said refrigerant expander means and extending outwardly therefrom substantially across the space between said container means and said expander means.

20. In testimony whereof I hereunto affix my signature.

FREDERICK R. ERBACH.
